ARTICLE CONTROLLED RELEASE MECHANISM FOR POSTAL FRANKING MACHINES

Knut Oscar Odén, Stockholm, Sweden, assignor to Aktiebolaget Hadar Schmidt, Stockholm, Sweden

Application July 8, 1946, Serial No. 681,971

In Sweden October 6, 1943

8 Claims. (Cl. 101—235)

1

This invention relates to postal franking machines of the type in which a crank or handle is adapted to feed the letters through the machine in order to get the letters franked, that is, printed with the postage values, and in which a sensing member for a letter introduced into the machine, is connected by means of a lever with a revolution stop for said crank or handle, in such a way that the revolution stop is moved from a locking position when a letter is introduced into the machine.

The invention has for its object to create, in machines of said type, a device by means of which the revolution stop is, independently of the different thicknesses of the letters, locked again after one revolution of the handle or crank even if at this moment the letter has not yet entirely passed the sensing member because of the length of the letter being too great. A further object is to obtain this result by means of a device which is easily actuated and is reliable in operation.

According to one feature of the invention a coupling or clutch is arranged in the connection from the sensing member to the revolution stop, which clutch is not disengaged under the action of the sensing member until this member has performed a movement which is of greater magnitude than that caused by a letter of normal thickness.

According to another feature of the invention means are provided for lifting an introduced letter of usual thickness, to effect said greater movement, as well as means for effecting this lifting only after the crank or handle has been turned from locking position.

According to another feature of the invention, when said greater movement is effected by introducing a letter of an especially great thickness, the revolution stop is engaged by a holding dog which is again released after the crank or handle has been turned from the locking position.

According to another feature of the invention a cam disc having a zero position recess, is securely mounted on the same shaft as the curved disc of the revolution stop, said zero position disc being adopted to engage a zero position stop and thereby to hold the crank or handle in a such zero position that the revolution stop can be moved from the locking position without frictional resistance.

One embodiment of a device according to the invention is by way of example illustrated diagrammatically in the annexed drawings.

Figs. 1A and 1B are vertical elevations, on the line I—I of Fig. 2, showing the essential elements of a franking machine but omitting details not essential for the understanding of the invention.

Fig. 2 shows a vertical cross section on the line II—II in Fig. 1B, the dog and the zero position cam disc with the zero position stop being omitted.

2

Fig. 3 shows the same cross section as Fig. 2 but the details being in the position which they occupy after the introduction of a thin (light) letter into the machine.

5 Fig. 4 shows the same cross section as Fig. 2 but the dog and the other details being in the position which they occupy after the introduction of a thick (heavy) letter.

10 Fig. 5 shows a cross section on an enlarged scale, the zero position cam disc and the zero position stop being in a position corresponding to that of Fig. 4.

15 Fig. 6 shows on another scale a modification of the franking machine, as seen from the front side and in a longitudinal vertical section.

15 Fig. 7 shows a vertical cross section substantially on the line VII—VII in Fig. 6.

20 Fig. 8 shows a vertical cross section of some details substantially on the line VIII—VIII of Fig. 6.

25 In the drawings, see especially Figs. 1A and 1B, reference numeral 1 denotes the bottom plate of the machine, 2 one of the end-walls, 3 the other end-wall, 4 an intermediate wall, 5 a crank or handle to feed or move the letters through the machine for franking the same, viz. printing postage values on the letters, and 6 a table for the letters. Between the walls 2 and 4 the well-known totalizers of the machine with associated 30 means (not shown) as well as some other details, among them also details of the present device, are arranged.

35 The printing drum 9 (Fig. 2) carrying the printing stamps 9' is mounted on the right end portion (Figs. 1A and 1B of the shaft 7 of the actuating crank handle 5, that is between the walls 3 and 4, the shaft 7 extending through the whole machine. A counter pressure roller 8 (Figs. 2—4) mounted below the printing drum, 40 is moved upwards against the printing drum when the letters are to be fed through the machine. In the embodiment shown the printing drum 9 is located a substantial distance above the table 6, as indicated in Fig. 2, and the counter pressure roller 8 is positively driven only during a part of the revolution of the printing drum, viz. from a moment just before the stamps 9' of the printing drum engage the letter. This driving of the counter pressure roller is effected 45 in any suitable well-known way, for instance from a Maltese cross wheel on the shaft 7 as will be described in connection with Figs. 6—8. Furthermore, the counter pressure roller 8 is lifted against the printing drum not until the 50 handle has been rocked through a predetermined angle, preferably immediately before the franking (printing) operation. This lifting can be effected by means of a cam disc on the shaft 7, and by means of levers operated by said cam 55 disc and actuating the mountings of the counter roller as will be described in connection with Figs. 6—8. The counter roller 8 carries on each 60 end a shoulder or a similar member 10. The

letter P' (Fig. 3) or P'' (Fig. 4) is introduced to contact with these two members 10 which serve as stops to limit the introduction of the letters. The members 10 are resiliently mounted in radial slots in the counter roller and are adapted to be forced or drawn into the counter pressure roller when this roller is lifted against the printing drum.

A fork-shaped rocking element comprising an intermediate piece 16 and two lateral legs 17, 18 is pivoted on a horizontal shaft 15 which is mounted between the walls 2 and 4 and is parallel to the main shaft 7. One of the legs, viz. the revolution stop leg 17, is by the action of its weight held in engagement with a stop shoulder 19' on the revolution stop cam disc 19 which is fixed to the main shaft 7. The other leg, viz. the control leg 18, carries a coupling pawl 21 pivoted on a horizontal axis 20. This pawl is by means of a spring 22 yieldingly depressed into a substantially horizontal position in which it is engaged by a coupling dog 23 which is pivoted on a horizontal axis 24. This axis is carried by one end of a double armed lever 26, 27 which is pivoted in the intermediate wall 4 by means of an axis 25 and is balanced by means of a counter weight 28. Under the action of a body 23' serving as counter weight the coupling dog 23 is normally held in a position in which it projects beneath the coupling pawl 21 and is engaged by the same. One arm 27 of the balanced lever constitutes the sensing member for the letters and the other arm 26 of the same constitutes a control member for the rocker 16, 17, 18. The spring coupling or clutch 21, 22, 23 disposed between the control arm 26 of the balanced lever and the control leg 18 of the rocker is of such construction, that the dog 23 is drawn upwards past the pawl 21 and will release this pawl when the sensing arm 27 is swung upwards approximately into the position shown in Fig. 4, either this is effected already by the introduction of a heavy letter P'' against the shoulders 10, as in Fig. 4, or when a light letter P' is lifted against the printing drum during the upward motion of the counter roller 8.

A holding dog 31 mounted on a pin 30 in the frame of the machine, is disposed in such manner, that the revolution stop leg 17 with its projection 17' engages the dog when the sensing arm 27, after disengagement of the spring clutch 21, 22, 23, has performed a lifting movement of sufficient magnitude. Said dog is not shown in Figs. 2 and 3 in order to make these figures more clear, but is illustrated in Figs. 1A, 4, and 5. The holding dog 31 is provided with a releasing arm 32 which is securely attached to the dog and by means of which the dog is lifted out from engagement with the revolution stop leg 17 after the spring clutch connection 21, 22, 23 provided between the rocker 16, 17, 18 and the balanced lever 26, 27, has been interrupted and after the handle 5 has been turned through an angle of such magnitude that the revolution stop disc 19 has moved from locking position.

For this purpose the main shaft 7 is provided with a second cam disc 33 which is arranged beside the revolution stop disc 19 and is coaxial with the same, and a lever 34 carrying a cam follower roller 35 is yieldingly held against said disc 33 under the action of a draw spring 37 connected with a spring holding member 36 in the frame of the machine (these details are shown only in Fig. 5). When the handle 5 and the shaft 7 are in the locking position, the lever 34 with its roller 35 is in a recess in the disc 33. In turning the

shaft 7 the cam follower roller 35 runs up on the raised portion of the circumference of the disc 33, the lever 32 then being actuated by the lever 34 and releasing the dog 31 from engagement with the revolution stop leg 17.

Furthermore, the disc 33 is adapted, by its engagement with the cam follower roller 35, to hold the main shaft 7 together with the revolution stop disc 19 in such zero position, that a clearance is present between the engaging end of the revolution stop leg 17 and the locking shoulder 19' of the revolution stop disc 19 and, thus, the first-mentioned element may be moved from the locking position without any frictional resistance. Consequently, the disc 33 at the same time serves as a zero positioning disc. However, it is of course possible to arrange a separate zero positioning cam disc.

Now, the manner of action when a letter P' of usual thickness (a thin or light letter) is introduced, is to be described. When a light letter P' is introduced to contact with the shoulders 10 of the counter pressure roller 8, the sensing arm 27 is lifted so much that the revolution stop leg 17 is lifted from its engagement with the revolution stop disc 19, but the spring clutch 21, 22, 23 is not disengaged. The parts are in the positions shown in Fig. 3. If now the operator, for any reason, should desire to take out the letter again, he may do so and the machine thereby locked again without any necessity of turning the handle one revolution, the machine being ready for a new run when a new letter is introduced. When the operator, after the introduction of the letter P', begins to turn the handle, at first the parts 31, 32 are actuated by the lever 34, but this actuation is only an idle one and said parts have no purpose to fulfill in franking light letters. After the printing drum in the continued rotation of the handle has turned its franking stamps downwards, the counter roller 8 will lift the letter upwards against the printing drum and the sensing arm 27 is lifted correspondingly, the spring clutch 21, 22, 23 now being disengaged because the dog 23 slides over the pawl 21. Thus, the revolution stop leg 17 will drop onto the revolution stop disc 19, so that the revolution stop leg 17 can arrest the revolution stop cam disc 19 when this disc has made one revolution. The interruption of the connection between the rocker and the balanced lever is necessary in order to stop the handle after one revolution even if the letter is of such great length that it in this moment has not passed entirely by the sensing arm. After the letter has entirely passed the sensing arm 27, by being drawn out by hand, the balanced lever 26, 27 returns to its position of rest (Fig. 2), the dog 23 passing downwards over the pawl 21 and engaging the pawl under the action of the counter weight 23'.

When a heavy letter P'' of especially great thickness is introduced, the operation is another. At the very moment when the letter is inserted, the sensing arm is lifted to such high position, that the spring clutch 21, 22, 23 is disengaged and the revolution stop leg 17 is caught by the holding dog 31. Now, the parts are in the position shown in Figs. 4 and 5. If the operator then begins to turn the shaft, by means of the handle, the holding dog 31 is released by the elements 32, 34, so that the revolution stop leg 17 will again drop onto the revolution stop disc 19. Thus, this is effected not until the locking shoulder 19' of the revolution stop disc 19 has moved from the lock-

ing position in the direction of the arrow shown in Figs. 4 and 5. Consequently, the revolution stop leg 17 is ready to stop the handle 5 and the shaft 7 after the disc 19 has made a complete revolution. After the letter has passed entirely by the sensing arm 21, the details return to the position of Fig. 2, in the manner already described.

It will be understood that if the holding dog 31 were not provided, the revolution stop leg 17 would drop back into engagement with the locking shoulder of the revolution stop disc immediately upon the introduction of the heavy letter P" to contact with the shoulders 10 and after the disengagement of the spring clutch 21, 22, 23; consequently it then would not be possible to turn the handle. Thus, the holding dog 31 is provided only in view of the possibility of using the machine for the franking of letters of especially great thickness. If it would be possible to devise the machine only for the franking of light letters, the holding dog 31 would not be required, because in this case the spring clutch 21, 22, 23 is disengaged, viz. the connection between the rocker and the balanced lever is interrupted not until the locking shoulder of the revolution stop disc has moved from the locking position. However, regardless of whether the letters are light or heavy, the revolution stop leg 17 is moved from the engagement with the revolution stop disc just as the letter is inserted to contact with the shoulders 10 of the counter roller 8.

The device described and illustrated is of a comparatively simple construction and operates in a reliable manner. It is easily actuated and the letter causes a motion of only small weights when operating the sensing arm. The resistance which the letter has to overcome, is only that of the unbalanced weights of the details which take part in the movement of operation. Of course it would be possible to use springs for returning these details to the position of rest, but it is preferred to use the device illustrated, in which the own weight of the details (the gravity) performs this action.

In Figs. 6, 7 and 8 the reference numeral 101 indicates the bottom plate of the machine, 102 one of the end-walls, 103 the other end-wall, 104 the intermediate wall, 105 the crank or handle, 106 the table, 107 the main shaft geared to the handle, 108 the counter pressure roller, 109 the printing drum, and 109' the printing stamps. The roller 108 is journaled on knee levers 110 mounted on stationary pins 111 in the frame. By means of the tension springs 112 the levers are held against pins 113 on rocking elements 114 also mounted on the stationary pins 111. A link 116 has one end connected with the rocking elements at 115 and has its other end connected with an arm 117. This arm is securely mounted on the shaft 118 rotatably mounted in the frame. A second arm 119 is attached to the shaft 118 and carries a roller 120 which is cooperating with a cam disc 121 securely mounted on the shaft 107. The shaft 107 carries also a gear wheel 122 fixed to the same and meshing with a second gear 123 mounted on the shaft 124. This shaft 124 is connected with the central shaft 125 of the counter pressure roller 108 by means of the tubular shaft 126 and two universal joints. The gear wheel 122 has its teeth entirely cut away on a portion of its circumference as indicated by 122'

in Fig. 8, and is on one side connected with a curved disc 127, which on a portion 127' of its circumference, coinciding with the non-teethed portion of the wheel 122, has a radius corresponding nearly with the radius of the tops of the teeth of wheel 122, and which on the remaining portion of its circumference leaves the teeth of wheel 122 entirely free. The wheel 123 has one tooth 123' cut away laterally to an extent corresponding to the thickness of the disc 127. Thus, the wheel 122 will drive the wheel 123 only when the toothed part of wheel 122 meshes with wheel 123, but during the remaining part of the revolution there are no teeth on the wheel 122 to engage and drive the wheel 123, but the portion 127' of the disc 127 will be in sliding engagement with the tooth 123' and will hold wheel 123 against rotation by engaging the tops of the teeth of wheel 123. The parts 122, 123, and 127 constitute a kind of Maltese cross gear operating intermittently and driving the pressure roller 108 only during a part of the revolution of the printing drum 109.

In the position of rest the details are in the 25 position illustrated in Figs. 6 and 7. After a letter has been introduced on the table 106, the shaft 107 is rotated by means of the handle 105. Thereby, the roller 120 is operated by the cam disc 121, and the levers 110 are rocked by means of the arms 119, 117, the line 116, and the spring 112 such that the counter roller is lifted immediately before the printing operation and thereby the letter is raised to contact the printing drum. At the same time the counter pressure roller is driven over the mechanism 122, 123, 124, 125, 126, whereby the letter is fed through the machine and the franking value is printed thereon when the stamps or printing types 109' engage the letter. The Maltese cross gear 122, 123, 127 is such that the counter pressure roller starts its rotation not until the stamps 109' engage the letter, and this positive rotation is continued until the letter is delivered from the machine. Then, the roller 120 slides on a lower portion of the cam disc 121, whereby the counter pressure roller is lowered to the position shown in Figs. 6 and 7.

What I claim is:

50. 1. A machine for printing franking values directly upon letters inserted in the same, comprising, in combination a printing drum, a handle for actuating the machine to move letters through the machine for printing postage values upon said letters, a revolution stop for said handle, for locking said handle when in a locking position, and allowing movement of said handle when in a position of release, a movable sensing member for sensing the presence of a 55 letter introduced into the machine, a lever connection between said sensing member and said revolution stop, to move said stop from locking position to unlocked position when a letter is introduced into the machine, a clutch arranged 60 in said connection for disengaging said connection and having means for delaying disengagement of said lever connection until after said sensing member has performed a movement of greater magnitude than that caused by a letter of a predetermined thickness, and a counter pressure roller mounted below said printing drum and movable upwards against said drum after the handle has been moved from its initial position, to lift an introduced letter of predetermined thickness whereby the sensing member is moved 65 70 75

further and the stop is freed to return to locking position.

2. A machine for printing franking values directly upon letters inserted in the same, comprising, in combination, a printing drum, a handle to rotate said drum and to move letters through the machine to have postage values printed thereon, a revolution stop for said handle, for locking said handle when in a locking position, and allowing movement of said handle when in a position of release, a movable sensing member for sensing the presence of a letter introduced into the machine, a lever connection between said sensing member and said revolution stop, to move said stop from locking position to unlocked position when a letter is introduced into the machine, a clutch arranged in said connection for disengaging said connection and having means for delaying disengagement of said lever connection until after said sensing member has performed a movement of greater magnitude than that caused by a letter of a predetermined thickness, a counter pressure roller mounted a definite distance under the printing drum and movable upwards against the same after the handle has been turned from its initial position to lift an introduced letter of predetermined thickness and thereby to lift the sensing member, a dog for holding the revolution stop out of locking position upon insertion of a letter of greater than the predetermined thickness, and means for releasing the revolution stop from said dog after the handle has been turned from its initial position.

3. A machine for printing franking values directly upon letters inserted in the same, comprising, in combination, a printing drum, a handle to rotate said drum and to move letters through the machine to have postage values printed thereon, a revolution stop for said handle, a horizontally pivoted double armed lever, one arm of which constitutes a sensing member for a letter introduced into the machine, a lever connection between the other arm and said revolution stop, to move said stop from locking position to unlocked position when a letter is introduced into the machine, a clutch arranged in said connection for disengaging said connection when released and having means for delaying disengagement of the clutch until after said sensing arm has performed a movement of greater magnitude than that caused by a letter of predetermined thickness, a counter roller mounted a definite distance under the printing drum and movable upwards against the same after the handle has been turned from its initial position to lift a letter introduced to contact with the counter roller and also to lift the sensing arm, a dog for holding the revolution stop out of locking position upon insertion of a letter of greater than predetermined thickness, and means for releasing the revolution stop from said dog after the handle has been turned from locking position so that the stop returns to position for locking the handle upon completion of cycle of operation.

4. A machine for printing franking values directly upon letters inserted in the same, comprising, in combination, a printing drum, a handle to rotate said drum and to move letters through the machine to have postage values printed thereon, a horizontally pivoted double armed lever, one arm of which constitutes a sensing member for a letter introduced into the machine, the double-armed lever being caused to swing

by engagement of the sensing arm with a letter, a horizontally pivoted fork-shaped rocker, one leg of which constitutes a revolution stop for the handle and the other leg of which is releasably connected with the other arm of said double armed lever, so that when the sensing arm is engaged by a lever the stop is rocked to unlocked position, a clutch between the double armed lever and the rocker for disengaging the connection between said lever and said rocker said clutch having means for delaying disengagement of said connection between the lever and rocker until said sensing arm has performed a movement of greater magnitude than that caused by a letter of usual thickness, a counter roller mounted spaced beneath the printing drum and movable upwards against the same after the handle has been turned from its initial position, to lift a letter introduced into contact with the drum and thereby also to lift the sensing arm, a dog for holding the revolution stop leg out of locking position upon insertion of a letter of greater than ordinary thickness, and means for releasing the revolution stop leg from said holding dog after the handle has been turned from its initial position so that the stop returns to position for locking the handle upon completion of the cycle.

5. A franking machine as claimed in claim 4, and in which the clutch comprises in part a coupling pawl which is horizontally pivoted on the rocker and which is yieldingly depressed by a spring into an approximately horizontal position, and in part a coupling dog which is horizontally pivoted on the double armed lever and is normally held by yieldable means in engagement under the coupling pawl but is adapted to be drawn upwards over the coupling pawl to disengage the same by the action of the double armed lever either when the counter roller lifts a letter of usual thickness, or at the very moment when a letter of especial great thickness is introduced.

6. A franking machine as claimed in claim 4 and in which the revolution stop leg is positioned to rest upon a revolution stop cam disc after the rocker has been disconnected from the double armed lever and to drop onto said revolution stop disc after one revolution, to stop this disc even if the letter on account of great length has not fully passed the sensing arm.

7. A franking machine as claimed in claim 4, and in which the same shaft carries a revolution stop cam disc and a zero position cam disc having a zero position recess, and that a zero positioning stop holds said zero disc in such zero position that a clearance is present between the revolution stop leg and the revolution stop disc.

8. A franking machine as claimed in claim 4, and means for driving the counter roller positively only during a part of the revolution of the printing drum, that is, from a moment immediately before the franking stamps of the printing drum engage the latter.

KNUT OSCAR ODÉN.
